US00D557376S

(12) **United States Design Patent** (10) Patent No.: **US D557,376 S**
(45) Date of Patent: **** Dec. 11, 2007**

(54) **DECONTAMINATION NOZZLE**

(75) Inventors: **Richard Zerrer**, Wooster, OH (US);
Roger Flagler, Cincinnati, OH (US)

(73) Assignee: **RHBA Acquisitions, LLC**, Shreve, OH
(US)

(**) Term: **14 Years**

(21) Appl. No.: **29/267,134**

(22) Filed: **Oct. 4, 2006**

(51) LOC (8) Cl. **23-01**

(52) U.S. Cl. **D23/213**

(58) Field of Classification Search **D23/213;**
239/548; 169/37

See application file for complete search history.

(57) **CLAIM**

The ornamental design for a decontamination nozzle, as shown and described.

DESCRIPTION

FIG. 1 is a perspective view of a decontamination nozzle showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof; and,

FIG. 8 is a perspective view similar to FIG. 1 with spray nozzles attached to the decontamination nozzle shown in broken lines.

The broken lines used in the drawings are for illustrative purposes and do not form part of the claimed invention.
